UNITED STATES PATENT OFFICE.

HENRY E. PELLETIER, OF NEWARK, NEW JERSEY, ASSIGNOR TO PELLETIER PRODUCTS MFG. CO., INC., OF ELIZABETH, NEW JERSEY, A CORPORATION OF NEW JERSEY.

VALVE.

1,381,223.

Specification of Letters Patent. Patented June 14, 1921.

Application filed November 8, 1920. Serial No. 422,475.

To all whom it may concern:

Be it known that I, HENRY E. PELLETIER, a citizen of the United States, residing in Newark, in the county of Essex and State 5 of New Jersey, have invented certain new and useful Improvements in Valves, of which the following is a specification.

This invention relates to improvements in valves, such as are used to control the inlet 10 and exhaust ports of internal combustion engines, the valves consisting of disks, having beveled edges fitted to conical seats, against which they are normally held by spring pressure, the valves being periodically raised in sequence by cams or tappets 15 fixed on a shaft actuated by the engine.

In valves of this character it is requisite that a close and accurate joint be maintained between the valve and its seat in order 20 to insure proper and economical working of the engine.

Experience shows that such fit is difficult to maintain, for the valves and seats are subject to erosion from the passage of both 25 fresh and spent gases, the deposit of carbon in the exhaust valves, and from the constant and rapid repetition of hammer-like blows of the valve against its seat in closing, aggravated by the fact that the valve merely 30 moves from and to its seat, so that identically the same surfaces are always brought into repeated contact.

A further difficulty is encountered by the disposition of the valve to become distorted, 35 both by transverse elongation in one direction, thus assuming an elliptical shape, and in buckling in an axial plane, these changes being caused by necessarily subjecting different parts of the valve to different degrees 40 of heat, caused by the effect of the explosions being directed upon one part more than another, sufficient to effect the molecules of the metal, creating a condition that necessitates frequent resurfacing and re- 45 grinding.

The object of this invention is to overcome these difficulties by providing a valve which rotates partially with respect to its seat at

each time it is raised, the effect being to equalize the internal stresses set up by the 50 impingement of heated gases, and due to the rotary motion imparted to it, automatically free the contacting surfaces from any deposits, equalize the wear, producing a self-grinding effect and maintaining an accurate 55 joint at all times when the valve is closed.

This and other objects, which will become apparent as the description progresses, is attained by the novel construction and arrangement of parts hereinafter described 60 and shown in the accompanying drawings, forming an essential part of this disclosure, and in which:—

Figure 1 is a longitudinal sectional view showing a conventional type of tappet valve 65 and its operating means as arranged in conformity with the invention.

Fig. 2 is a similar view taken in a plane at a right angle to Fig. 1, the valve being in a raised position.

Fig. 3 is a bottom plan view of the rotator sleeve.

Fig. 4 is a diagrammatical view of the rotator developed.

Fig. 5 is a top plan view of the outer 75 member of the rotator.

Fig. 6 is a fragmentary development of the same.

Referring to the drawings in detail, the numeral 10 designates the valve shaft of an 80 internal explosion engine, the same having secured to it one or more cams or tappets 11 arranged to operate the several valves in proper sequence, the shaft being driven by the valve gear of the engine and supported 85 in appropriate housings fixed to its frame.

A casing 12 contains the ports, both inlet and exhaust, the chambers 13 communicating with the source of fuel supply or outlet for spent gases as the case may be.

The valve seats 14 are formed directly in the element 12, in register with the chambers 13 and are of the usual conical type.

The casing 12 contains bored openings 15 leading to the chambers and frictionally engaged therein is a sleeve or bushing 16 hav-

ing an annular flange 17 resting against the outer surface of the casing 12, an integral collar 18 being on the opposite side of the flange, from which a hollow stem 19 ex-
5 tends.

A disk valve head 20, having a crowning outer surface containing a slot 21 and beveled contact edges 22 suited to the seat 14, is formed with a spindle 23 which is fitted to
10 move freely in the axial opening of the sleeve 16 and stem, its extending end being secured in a holder 24 containing a freely movable sphere 25 against which the cam or tappet 11 makes contact in raising the valve
15 from its seat.

The anti-friction device may be omitted if desired and the cam make direct contact on the end of the spindle.

A tubular sleeve 26 surrounds the lower 20 end of the stem 19, the sleeve having an annularly flanged base 27, between which and the flange 17 is disposed a helically coiled compression spring 28, guided by the collar 18 and exterior of the sleeve 26, the sleeve 25 being secured to the spindle 23 by a pin 29 passing through both elements.

Thus at each revolution of the shaft 10 the valve will be opened, and closed as the cam continues to rotate by the spring 28, the 30 action being purely axial.

In order to partially rotate the valve relative to its seat at each axial movement, the lower end of the stem 19 has formed on its outer surface a plurality of projections 30, 35 resembling right angled triangles, arranged in uniformly spaced relation around the circumference of the stem, the bases of the triangles being toward the flange 17 and their perpendiculars 31 alined with the axis of the 40 stem.

A second series of projections 33 are formed at the extreme end of the stem, these being parallelograms with the lower corners removed, their upper longer edge 34 being 45 arranged diagonally at substantially right angles to the diagonal faces 32 of the triangles, which, if the lines were extended would approximately cut the centers of the edges 34, while the end edges 35 are par-
50 allel with the perpendiculars.

Coöperative internal elements 36 are formed with the extreme upper portion of the surrounding tubular element 26, these projections intersectingly engaging the edges 55 35 as the sleeve 26 moves over the stem 19, making contact with the angular edges 32, causing a torsional or twisting effect, transmitted by the sleeve to the valve spindle, which is continued during its full outward 60 movement.

The projections 36 then engage with the edges 34, as the sleeve moves in an opposite direction, further increasing the turning movement of the valve until it is again seat-

ed, thus transmitting reciprocating rectilinear motion into intermittent rotary motion.
65

The direction of rotation of the valve as shown is clock-wise, but this depends on the disposition of the spiral paths between the angular edges 32 and 34, while the degree of 70 angularity or pitch given these edges is dependent upon the number of projections used and which corresponds to the fractional portion of a revolution it is desired to impart to the valve at each lineal movement, four being indicated, although any number from 75 three to eight may be used with good results.

From the foregoing it will be clear that that the action imparted to the valve is a 80 compound of longitudinal and rotary motion, taking place simultaneously, but not uniformly, as the valve is moved straight out at the commencement, then relatively slowly turned as it approaches the limit of its outward movement, allowed to partially close by a straight movement and accelerated rotary movement at the latter part, causing it to contact upon the seat with a rubbing or grinding action.
90

This action effectively cleans the surfaces from any deposits of carbon or the like and causes uniform wear of the contacting surfaces assuring a tight joint, further enhanced by subjecting the disk valve to heat 95 uniformly in its different portions.

The foregoing disclosure is to be regarded as descriptive and illustrative only, and not as restrictive or limitative of the invention, of which obviously an embodiment may be 100 constructed including many minor modifications without departing from the general scope herein indicated and denoted in the appended claims:

1. A valve of the class described comprising- 105 a disk, a seat receptive of the disk, a spindle on said disk, means for guiding said spindle, a sleeve fixed on the spindle, means for intermittently moving said spindle and disk in an axial plane and integral means 110 formed on said sleeve coöperative with said spindle guiding means for partially rotating said valve and spindle at each axial movement thereof.

2. A valve of the class described comprising- 115 a disk, a seat receptive thereof, a spindle fixed on said disk, a guide for said spindle, a sleeve surrounding the lower end of said guide, said sleeve being fixed to the spindle, means for imparting intermittent rectilinear motion to said spindle, means formed exteriorly on the lower end of said guide and integral means formed internal of said sleeve coöperative with said second named means whereby the sleeve, spindle and disk are 120 caused to partially rotate at each rectilinear movement thereof.
125

3. A valve of the class described comprising-

ing a disk, a seat receptive thereof, a spindle fixed on said disk, a guide for said spindle, a sleeve fixed on said spindle into which said guide enters, means for moving said spindle and sleeve rectilinearly in said guide and cooperative means formed with said guide and sleeve respectively whereby said valve disk is directed to rise from the seat axially, par-

tially rotate when raised and make contact with its seat with a rotary motion.

This specification signed and witnessed this fourth day of November, 1920.

HENRY E. PELLETIER.
